UNITED STATES PATENT OFFICE.

DANA E. WESCOTT, OF SOUTH BEND, INDIANA, ASSIGNOR TO LOUIS M. HAMMER-SCHMIDT, TRUSTEE, OF SOUTH BEND, INDIANA.

CUT-OUT FOR ELECTRIC-LIGHTING SYSTEMS.

1,313,438.

Specification of Letters Patent.

Patented Aug. 19, 1919.

Application filed March 31, 1916. Serial No. 88,124.

To all whom it may concern:

Be it known that I, DANA E. WESCOTT, citizen of the United States, residing at #729 So. Mich. street, South Bend, in the county 5 of St. Joseph and State of Indiana, have invented certain new and useful Improvements in Cut-Outs for Electric-Lighting Systems, of which the following is a specification.

10 This invention relates to cut-outs for electric lighting systems and has for its particular object to provide means which when operated by a solenoid in one direction will serve to prevent the closing of a switch in 15 a lamp circuit, and when again operated in the same direction, will allow said switch to close.

This device is particularly adapted for use 20 in lighting systems wherein it is desirous of extinguishing some of the lamps previous to the others, and performing the function by a control which is located at a central station.

These and other objects hereinafter described, are attained by the means illustrated in the accompanying drawing, in which:

Figure 1 is a diagrammatic view showing two auxiliary lamp circuits connected to an 30 arc-lamp circuit by the improved cut-out.

Fig. 2 is a side elevation of a portion of the cut-out.

Fig. 3 is a detail perspective view of the lower end of the suspension bar shown in 35 Figs. 1 and 2, and

Fig. 4 is a view in elevation of the notched members of the cut-out shown in a flattened condition.

Similar reference numerals in all of the 40 figures of the drawing designate like parts.

To more fully set forth the use of the invention, it is herewith illustrated in connection with a lighting system described and claimed in an application for patent Serial 45 Number 88,125, filed March 31, 1916, and which forms no part of the present invention.

As shown in the drawing, there is connected in series with an arc-lamp circuit 5 50 a pair of solenoid magnets 14, which control a double core 15, and the same carries a contact plate 16 whose ends are adapted to engage with the stationary contacts 17, to close the auxiliary lamp circuits 18 and 19 55 and which receive power from any suitable

source, preferably through a transformer 20 of a primary circuit 13. The lamps 23 and 24 respectively of these circuits are connected in multiple therewith.

It being desirous of extinguishing the 60 lamps of one circuit before those in another circuit, in this case the lamps 23, the improved cut-out is provided which is constructed as follows: Contact plate 16 is provided on its upper side with an insulating 65 block 24 provided with a central aperture through which passes a rod 25, which also passes through an aperture in said contact plate 16. Said rod is provided with a head 26 which is larger than the diameter of the 70 aperture in block 24 and by which the rod is suspended. The lower end of the rod is provided with a cross-arm 27 which is adapted 75 to engage the edges of the teeth 28 and 29 in the cylindrical members 30 and 31 to rotate said rod and arm. These cylindrical members are supported in a suitable frame 32 and said rod 25 passes freely through said members 30 and 31 which are spaced apart 80 with their teeth disposed opposite each other. The cross-arm is positioned between said members in a position to reciprocate from engagement with one member to the other. The teeth of member 30 are formed with 85 notches of equal depth between them, and those of the member 31, are formed with alternate deep and shallow notches, (as clearly shown in Fig. 4 of the drawing) and the teeth of one set or member are arranged in staggered relation to the teeth of the other 90 member.

Thus it will be seen that when the cross-arm 27 drops downward from a deep notch in the member 31, (as shown in Fig. 3) it engages the inclined edge of a tooth in member 30 which forces it sidewise in its course to the bottom of the notch and consequently rotates the rod 25 beyond the vertical alignment of the point of the next tooth in the member 31, so that in moving upwardly 100 it will engage the inclined edge of said tooth which will guide it to the next notch and in position to engage another tooth in the member 30 when it again descends.

The contact plate 16 is resiliently sup- 105 ported from the core 15 by providing springs 33, which are supported on nuts 34 adjustably secured on the lower ends of suspension rods 35 which are secured in any desired manner to the core 15. These suspension 110

rods 35 are preferably positioned one on each side of the rod 25 and pass freely through apertures in the block 24 and the contact plate 16, it being understood, that none of the several parts of the cut-out device are ever in contact with the plate 16. By supporting the plate 16 in the manner described, it is obvious that the core can move a slight distance independently of the plate 16, so that any slight variation in the voltage of the arc-lamp circuit, will not disturb the engagement between the plate 16 and its contacts, thereby furnishing to the lamps 23 and 24 an even power which will give a steady light.

As shown in the drawing, circuits 18 and 19 are preferably formed with three wires, one wire 36 being common to both circuits, and together with a wire 37 forms the circuit 19, and said wire 37 is connected to the terminal of one member 37' of the transformer 20, and the remaining wire 38 of the circuit 18, is connected to one of the fixed contacts 17. The opposite contact 17 is connected to one terminal of another member 39 of the transformer 20, the other end of said member 39 being connected to the same terminal of the member 37' as is the wire 36. Thus the transformer member 39 is connected in circuit 18, while the member 37' is connected in circuit 19.

The operation of the device is as follows:—

Assuming that the parts are positioned as shown in Fig. 1, the lamps in all of the circuits are lighted. It now being desirous of extinguishing the lamps 23 in circuit 18 and keep them unlighted while the lamps in circuit 19 will continue to burn, the operator at the central station of the arc circuit 5 will momentarily open the switch 8 which will break the circuit 13 at the contacts 12. This will shut off the current furnished to the circuits 18 and 19 and consequently extinguish all of the lamps in all of the circuits. Simultaneously the magnets 14 are deenergized, thereby allowing the core 15, plate 16, and rod 25 to descend. This will cause the cross-arm to descend from one of the deep notches in member 31, (as at 41 in Fig. 2) and engage the inclined edge of the tooth 42 in the member 30 which will direct it downward on an incline to the bottom of the notch and consequently rotate the rod 25. Immediately thereafter the operator returns the switch 8 to a closed position, which will at once energize the magnets 9 and 14 and the cores will be drawn upwardly. The upward movement of the core 10 will close the circuit 13. At the same time, the core 15 will ascend together with the plate 16, rod 25 and its cross-arm 27, but said cross-arm in moving upwardly from the notch of tooth 42, will engage the inclined edge in the tooth 43 in the member 31 and be directed into the

shallow notch of that tooth. This will limit the upward movement of the plate 16 and rod 25, and consequently prevent the ends of the plate 16 from engaging with the contacts 17 and thus keep the circuit 18 open 70 with its lamps 23 unlighted. The circuit 19 is not affected by the open circuit 18 and will receive current through the transformer from the circuit 13, and its lamps will remain lighted as long as this circuit is closed. 75

Should the member 31 be constructed with alternate deep and shallow notches, (as shown in the drawing) another opening and closing of the switch 8, will rotate the cross-arm into the next deep notch and this will 80 close the circuit 18 again and its lamps will be lighted.

It will be observed, that with this improved cut-out, a plurality of lamp circuits can be extinguished separately and at different times of the day or night by an operator located at a central station.

Having thus fully described the invention, what is claimed is:

1. A cut-out of the character described, comprising a plurality of fixed contacts, a plate for engaging said contacts to complete an electric circuit, a rod supported by said plate, means for resiliently supporting and positively moving said plate and rod in one direction and allowing them to operate in the opposite direction by gravity, a fixed frame, and coöperating means on said rod and frame to allow and prevent the engagement of the plate with said contacts by limiting 100 and varying the degree of reciprocation in the same direction of said rod.

2. A cut-out of the character described, comprising a plurality of fixed contacts, a plate for engaging said contacts to complete 105 an electric circuit, a rod rotatably supported by said plate, means for resiliently supporting and positively moving said plate and rod in one direction and allowing them to operate in the opposite direction by gravity, a fixed frame, and coöperating means on said rod and frame for rotating said rod to different positions to vary and limit the end-wise movement thereof to allow and prevent the engagement of the plate with said fixed 110 contacts.

3. A cut-out of the character described, comprising a plurality of fixed contacts, a plate for engaging said contacts to complete an electric circuit, a rod supported by 115 said plate, means for resiliently supporting and positively moving said plate and rod in one direction and allowing them to operate in the opposite direction by gravity, a fixed frame, and coöperating means on said rod and frame to allow and prevent the engagement of the plate with said fixed contacts on alternate movements in the same direction of said rod, said resiliently supporting means being constructed to allow 120 125 130

said moving means to move when the plate is stopped before reaching said fixed contacts.

4. A cut-out of the character described, 5 comprising a plurality of fixed contacts, a plate for engaging said contacts to complete an electric circuit, a rod supported by said plate and depending therefrom, means for resiliently supporting and reciprocating 10 said plate, a pair of fixed members having opposed toothed edges, means on said rod for engaging said teeth to rotate the rod, the

notches between some of the teeth of one of said members being deeper than the remaining notches, whereby said rod is allowed to 15 move farther at one time than another time when the rod is moved in the same direction.

In testimony whereof I affix my signature in presence of two witnesses.

DANA E. WESCOTT.
